UNITED STATES PATENT OFFICE.

TIM PENWELL AND HARRY E. BROWN, OF ELDORADO, KANSAS.

TRAP.

1,308,255.

Specification of Letters Patent.

Patented July 1, 1919.

Application filed November 16, 1918. Serial No. 262,899.

To all whom it may concern:

Be it known that we, TIM PENWELL and HARRY E. BROWN, citizens of the United States, residing at Eldorado, in the county 5 of Butler, State of Kansas, have invented a new and useful Trap, of which the following is a specification.

The subject of this invention is a trap intended for use in fishing plunger rods, or 10 other obstructions, from wells.

The main object of the invention is the provision of means for gripping the smooth surface of a rod or other obstruction.

Another object of the invention is the provision of means for yieldingly forcing the gripping element toward operative position.

Another object of the invention is to provide maximum play for the gripping element.

20 The invention also contemplates generally improving the construction and enhancing the utility of traps.

With the foregoing and other objects in view, which will appear as the description 25 proceeds, the invention resides in the combination and arrangement of parts and in the details of construction hereinafter described and claimed, it being understood that changes in the precise embodiment of the invention herein disclosed can be made within 30 the scope of what is claimed without departing from the spirit of the invention.

A practical structure for carrying out the invention is illustrated in the accompanying 35 drawing, wherein:—

Figure 1 is a view in longitudinal section of a trap constructed in accordance with the invention;

Fig. 2 is a cross section taken on the line 40 2—2 of Fig. 1;

Fig. 3 is a fragmentary view in elevation of the device.

Referring to the drawing by numerals of reference:—

45 In carrying out the invention a tubular member 1 is provided, which is threaded at one end to permit attachment to a section of rod or tubing 2, by which the device may be lowered into a well 1 the member having an upper bore 31. At the other end the tubing is reamed out to form a lower bore 30 and as indicated at 3, to provide a flaring mouth which will more readily guide a plunger rod or other obstruction into the tubing 1.

55 The tubing 1 is provided with an aperture

4, positioned between the ends of the tubular member, and the member is bored longitudinally from the threaded end to a suitable position at the aperture 4 so as to form an upwardly facing shoulder 5.

60

The tubular member 1 is drilled, as at 6, to form a passage or bore communicating with the aperture 4 adjacent the shoulder 5 for the reception of the trunnions 7 of the clapper or grip 8. The main bore is of 65 larger diameter than the bore 30. One end of the bore 6 may be enlarged and threaded for the reception of a short tubular socket 9, which receives one of the trunnions 7 and permits easy assembling of the device. The 70 free end of the clapper 8 normally rests upon the shoulder 5, and this end is provided with a substantially V-shaped notch 10, the edges of which are preferably beveled.

A leaf spring 11 is riveted or otherwise 75 secured within the tubular member 1, and is arranged longitudinally of the member to extend partially across the aperture 4. The free end of the spring 11 is preferably rolled, as at 12, and is positioned to engage 80 the clapper, when the same is swung upwardly by a rod 13 or other obstruction entering the member 1, and force the clapper against such obstruction to grip the same.

The operation of the device is as follows:—The member 1 is threaded onto a section of tubing 2, and sections of such tubing are joined until the member has been lowered into the well to a sufficient depth to encircle the end of the rod or obstruction. As 90 the member is lowered over the rod 13, the rod will push the clapper 8 and rock it upwardly upon its trunnions 7, which will allow the end of the rod to pass. By now drawing the member 1 upwardly from the 95 well, the clapper 8 will, through the spring 11 and the force of the upward pull, be forced to grip the rod tightly, the rod resting in the V-shaped notch. This will bend the rod over the edge formed by the shoulder 100 5 and will tend to firmly grip the rod and draw the same from the well.

The provision of the aperture 4 allows full swing of the clapper so that larger obstructions may readily be taken care of.

105

Having described the invention, what we claim as new and seek by Letters Patent, is:—

A device of the class described comprising a tubular member provided with upper and lower bores, there being a side opening in 110

the member, the lower bore being of smaller diameter than the upper bore to form an intermediate shoulder and to form a thickened part in the wall of the member below the shoulder, said thickened part having a transverse passage communicating intermediate its end with the lower bore; a grip adapted to move into the opening and to rest on the shoulder, the grip having trunnions insertible into the passage by way of the bores;

and a removable member in the passage, the member coöperating with one trunnion.

In testimony that we claim the foregoing as our own, we have hereto affixed our signatures in the presence of two witnesses.

TIM PENWELL.
HARRY E. BROWN.
